UNITED STATES PATENT OFFICE.

WILLIAM ROBINSON, OF BOSTON, MASSACHUSETTS.

ROLLER-SKATE.

SPECIFICATION forming part of Letters Patent No. 334,896, dated January 26, 1886.

Application filed August 7, 1885. Serial No. 173,817. (No model.)

To all whom it may concern:

Be it known that I, WILLIAM ROBINSON, a citizen of the United States, residing in Boston, in the county of Suffolk and State of Massachusetts, have invented a new and useful Improvement in Roller-Skates, (for which I have not obtained a patent in any country,) of which the following is a specification.

The principal object of my invention is to afford a simple and effective method of adjusting the tension of the rocker-springs, an object which I accomplish by the method hereinafter described.

My invention also embraces a skeleton frame of improved construction, whereby great lightness and strength are secured. It also embraces a rocker of improved construction, together with several details in construction hereinafter fully set forth.

20 In the accompanying drawings, which form a part of this specification, Figure 1 is a vertical central longitudinal section of the rear end of a roller-skate embodying my invention. Fig. 2 is a cross-section of the skate through the line $x x$, Fig. 1. Fig. 3 is a perspective view of the heel-clamp. Fig. 4 is a perspective view of the rocker. Fig. 5 is an inverted plan of the heel-plate for "half-clamp" skate, showing the methods of attaching strap to the 25 heel-plate and the heel-plate to the skeleton frame of skate. Fig. 6 is an elevation of a portion of the skeleton frame, showing the core still in place, and illustrating the method of casting the frame or pedestal with necessary holes in it. Fig. 7 is a perspective view of the adjustable follower. Fig. 8 shows a vertical cross-section of a modified combination of the follower and rocker. Fig. 9 is an elevation of the skeleton frame; and Fig. 10 is a vertical cross-section of the same, through the line $y y$, Fig. 9.

A is a skeleton frame provided at each end with a pedestal, B, composed in part of the jaws $a a$, between which the rocker C is pivoted on the rocker-pin E. The rocker C is preferably provided with the short lugs $b b$, Fig. 4, through which the rocker-pin E passes, the body of said pin lying deep in the depression c of said rocker. By this construction 45 it is only necessary to punch or drill through the lugs b , instead of through the whole length

of the rocker. Furthermore, the rocker-cushion D comes in contact with said rocker-pin—that is, close to the pivotal center of said rocker.

F is an adjusting-follower resting on the upper surface of the cushion D, and consisting of a threaded stem or screw, d , provided with the plate f , which forms the largely expanded head of said screw d . The follower F is provided with flanges g , projecting downwardly, 55 which overlap the sides of the rubber cushion D to a greater or less extent. The threaded stem d of the follower F enters the smooth hole i in the upper portion of the pedestal B, and preferably situated centrally between the jaws $a a$ thereof. The nut h on the threaded stem d finds a shoulder against the under side, k , of the upper portion of the pedestal, as shown, whereby, as is evident, any desired amount of compression or adjustment may be applied to 60 the cushion D by turning said nut h .

To further steady the action of the follower F, it is provided with slots $e e$, which engage the ribs $m m$ of the jaws $a a$ of the pedestal, which ribs act as guides for the follower and 65 prevent lateral motion of the same.

In Fig. 8 the sides $g g$ of the follower F are extended so as to inclose the sides of the cushion D and the side flanges, $g' g'$, of the rocker, as shown, for the purpose of preventing the 70 exertion of too great a crushing force on the rubber cushion.

The under side of the heel-plate H is provided with lugs $n n$ and $n' n'$, with space between each pair. (See Figs. 5 and 1.) These 75 lugs are placed astride of the longitudinal rib b , Figs. 6, 1, and 9, and hug the same closely. The bottom surfaces of said lugs rest on the upper horizontal surface, q , of the pedestal. Thus supported, a single screw, G, Fig. 1, passing through the hole G in the heel-plate, screws 80 into the top of the pedestal or frame and secures said heel-plate firmly in position. The toe-plate is secured to the opposite end of the skeleton frame in precisely the same manner. 90

In Figs. 1 and 2 the heel-plate is attached to the boot-heel by means of the clamps r , operated by the right-and-left-hand clamp-screws s in the usual manner. The clamp I provide with horizontally-arranged teeth t , with horizontal edges, as shown, which sink readily into the boot-heel and hold the skate firmly in po- 100

sition. A failure in this respect is a serious drawback with most of the "all-clamp" skates now in the market.

The skeleton frame or pedestal is provided, 5 between the jaws *a a* beneath the horizontal ribs *g*, with the slot *u*, in which the clamp-screw *s* fits at its center, whereby said clamp-screw is always held in proper relative position.

10 The heel-plate *H*, Fig. 5, has the rivets *v* cast integral with it, and by means of these rivets the heel-strap *I* is riveted to the heel-plate, as shown. This is the heel-plate for a half-clamp or an "all-strap" skate.

15 It will be understood that a half-clamp skate is readily converted into an all-clamp, or the reverse, by simply removing the screw *G*, taking off one plate, substituting the other therefor, and replacing the screw.

20 The jaws *a a* of the pedestal are provided with slots *w*, in which the rocker-pin *E* is free to move up and down, whereby, as is evident, the weight of the skater is supported on the cushions *D*. Thus the vibrations produced in 25 running over rough surfaces are absorbed, and the compression of the cushions varies according to the varying weight of different skaters—that is, the cushions become in a measure self-adjusting.

30 The rubber cushion *I* prefer to make in cross-section substantially of the form shown in Figs. 2 and 8—that is, flat on top with plane sides diverging downwardly, the bottom forming angles with the sides and descending slightly toward the center of rocker. With rubber made in this form, and the rocker conforming to the bottom of the same, I find that the rocking movement of the rocker tends to compress the rubber toward or beyond the center of the 35 plate *f* of the follower *F*—an important desideratum.

Fig. 6 represents the exact form of the pattern for the skeleton frame, in which *a' b' c'* are core-prints; or this figure may be considered 45 as representing the completed casting, with *a' b' c'* representing the position and conformation of the sand core, which of course must be identical in size and conformation with the core-print.

50 In casting the skeleton frame I use a pattern provided with core-prints, as already described. After molding the pattern I lay sand cores in the depressions made by the core-prints, close the mold, and cast the molten 55 metal into it. On opening the mold the casting comes out provided with the slots *w w* for the rocker-pin, the round, smooth hole *i* for the stem *d* of the follower *F*, and the hole *d'* for the screw *G*. The oblong piece *a'* and the 60 branches *b' c'* form, preferably, one branching core. Thus all necessary holes and slots are cast in the pedestals of the skeleton frame. By this means I am able to make the holes in the pedestals much more accurate, both absolutely 65 and relatively, than is possible when the holes are either punched or drilled. It is evident that in this way I save much labor, and am

able to make the skates much more rapidly and cheaply than is otherwise possible. Furthermore, the parts come together accurately 70 and in proper alignment, and form a more perfectly-running skate than can be made by any other method.

For skates having wooden foot-platforms the 75 pedestals are cast with holes exactly as described in connection with skeleton frames. The vertical rib or brace *j*, preferably made in the form of an arch, and the horizontal rib or brace *j'* connect the pedestal *B* at one end of the skate with an exactly similar pedestal at 80 the other end of the skate. The vertical rib *j* and the horizontal rib *j'* extend from pedestal to pedestal independently of each other, except that they are connected in the center by the post *k'*. This construction gives to the skeleton frame maximum strength and resistance to vertical and horizontal strain with minimum weight.

The rollers are attached to the rocker by means of an axle in the usual manner, and the 90 heel and toe plates are provided with guides of suitable construction, which it is not necessary here to show, for the clamps.

I do not herein claim the general design of the skate, as I shall claim that in an application to be filed hereafter.

What I claim as new, and desire to secure by Letters Patent, is—

1. In a roller-skate, the adjustable follower *F*, consisting, essentially, of the screw *d*, with 100 its expanded head *f*, in combination with the cushion *D*, and forced against the same by means of the nut *h*, turning on said threaded screw *d* and shouldering against the under side, *k*, of the upper portion of the pedestal, 105 substantially as described.

2. In a roller-skate, the adjustable follower *F*, consisting, essentially, of the screw *d*, with its expanded head *f*, provided with the flanges *g g*, adapted to overlap the edges of the cushion, substantially as described.

3. In a roller-skate, the adjustable follower *F*, consisting, essentially, of a screw with its expanded head, said follower being adapted to adjust the tension of the spring or cushion by 115 means of a nut turning on the threaded stem of said screw, substantially as described.

4. The adjustable follower *F*, consisting, essentially, of a screw with its expanded head, in combination with the guiding-ribs *m m*, projecting inwardly from the jaws *a a* of the pedestal and adapted to steady and guide said follower between said jaws, substantially as described.

5. In a roller-skate, the adjustable follower 125 consisting, essentially, of a screw with its expanded head resting on the cushion or spring, in combination with said cushion or spring, the guides *m m*, the hole *i* in the upper part of the pedestal, and the nut *h*, pressing against 130 the shoulder *k* of said pedestal and adapted to control the movement of said adjustable follower, substantially as described.

6. The rocker *C*, provided with the perfor-

rated lugs *b b* for the reception of the rocker-pin, the depression or hollow *c*, extending longitudinally between said lugs, and the unbroken webs or flanges *g' g'* on either side of said depression *c*, substantially as and for the purpose described.

7. The skeleton frame of a roller-skate, consisting, essentially, of two pedestals connected by two independent ribs or braces, *j j'*, with space between them, one of said ribs or braces being in a vertical plane and the other in a horizontal plane, substantially as described.

8. In the skeleton frame of a roller-skate, the combination, substantially as described, of the following elements: two pedestals connected by two ribs or braces with space between them, and a strengthening-post, *k'*, connecting said ribs or braces, one of said ribs or braces being wider horizontally than its vertical thick-

ness and the other deeper vertically than its horizontal width.

9. In a roller-skate, the adjusting-follower consisting, essentially, of a screw with its expanded head resting on the cushion *D*, in combination with said cushion, the jaws *a a* of the pedestal provided with the slots *w w* in a vertical plane, and the rocker *C*, pivoted in said slots, substantially as described.

10. In a roller-skate, the pedestal *B*, consisting, essentially, of the jaws *a a* and the upper plate connecting the same, cast with holes cored in said jaws and upper plate by means of two or more cores joined into one branching core, substantially as described.
